G. E. SMITH

EXERCISING DEVICE

Filed Dec. 11, 1922

FIG. 2

FIG. 1

FIG. 3

INVENTOR

George E. Smith
By Ray, Foster Brown,
attorneys

UNITED STATES PATENT OFFICE.

GEORGE E. SMITH, OF NEWARK, OHIO.

EXERCISING DEVICE.

Application filed December 11, 1922. Serial No. 606,190.

To all whom it may concern:

Be it known that I, GEORGE E. SMITH, a citizen of the United States, and resident of Newark, in the county of Licking and State of Ohio, have invented a new and useful Improvement in Exercising Devices; and I do hereby declare the following to be a full, clear, and exact description thereof.

10 My invention relates to exercising devices, and its object is to provide an improved device of simple construction, whereby physical exercise may be taken in an interesting manner by repeatedly raising a weight and depositing the weight in a vertical passage down which the weight falls at a rate sufficiently slow to avoid noise and shock. The weight is delivered from the bottom of the vertical passage and may be 15 again lifted and deposited as many times as may be desired, and the user of the device, by counting the number of times the weight is passed through the machine, can readily calculate the amount of work he has done.

20 The vertical passage into which the weight is deposited is made of the proper size and shape to fit the outlines of the weight with but little clearance. Therefore, as the weight descends in the vertical passage it will compress the air beneath it if the lower end is closed, or will rarify the air above it if the upper end of the passage is closed. I utilize this abnormal air pressure effect, either compression or rarification, to check the fall of the weight in the 25 vertical passage, and thus reduce the shock when the weight reaches the bottom of the passage. Other novel features of my device include means for closing either the upper end or the lower end of the vertical passage, means for adjusting the vertical height of the passage and means, in addition to the pneumatic means already mentioned, for cushioning the fall of the weight.

45 In the accompanying drawing, Fig. 1 is a vertical sectional view showing the device constructed in accordance with my invention, wherein the lower end of the vertical passage is closed and the height of the passage is adjustable; Fig. 2 is a similar ver-

tical sectional view showing a construction in which the upper end of the vertical passage may be closed while the weight is descending, and also showing a modified form of door for closing the lower end of the 55 passage; and Fig. 3 is an enlarged diametrical sectional view showing one manner in which the weights may be constructed.

In Fig. 1 of the drawing, the numerals 2 and 3 indicate telescoping tubes which define a vertical passage 4, and which are supported upon a hollow base 5. Suitable means are provided for adjusting the effective vertical height of the tube 3, such means, as shown, consisting of a thumb screw 6 extending through a screw-threaded opening in a band 7 formed around the upper end of the tube 3 and bearing against the upper side of the tube 3. Any other means for accomplishing the same result 70 may of course be employed.

A weight 9 which, as shown, is spherical, but which may be of any other desired form, is shown in various positions within the tube and the base. The weight is preferably fitted with a suitable covering of a soft rubber or a fabric with a soft nap, as shown at 9^a Fig. 3, so that in passing through the tube the covering will be crowded against the walls of the tube by the pneumatic 80 pressure existing therein, and the friction thus set up will assist in checking the fall of the weight. To the same end the inner walls of the vertical tube may be lined with soft rubber or soft fabric.

The base 5 contains a cushioning pad 10 of rubber or other soft material, the upper surface of which is suitably shaped to direct the weight from the vertical tube to a door 11 which swings on a horizontal pivot 12, 90 and which may be lined with felt or other suitable material, as shown at 13.

The door 11 should be of such weight and construction that a ball descending through the vertical passage will not force 95 the door open until the ball rolls against it. In Fig. 1 the weight of the door is relied upon to keep the door closed until it is pushed open by the weight. In the modification shown in Fig. 2 the door 11^a swings 100

from a pivot 12^a, as in Fig. 1, and is provided with a latch 15 which holds the door securely until it is released by the ball just before the ball engages the door. For this purpose the latch 15 hooks around a fixed pin 16 and is provided with a tail portion 17 which extends into the path of the descending weight 9. A spring 18 restores the latch to its active position after the ball 10 has passed beyond the door 11^a.

In the device shown in Fig. 2, the suction produced above the descending weight is relied upon to check its fall instead of, or in addition to, the compression of the air below the weight. For this purpose the upper end of the vertical tube 20 is closed by means of a door 21 which is pivoted at 22 and is provided with an arm 23 to which is attached a spring 24 that tends to hold 20 the door 21 in the open position shown in dotted lines. The door 21 also has an arm 25 which, when the door is open, projects partially across the upper end of the tube 20, so as to be engaged by the weight 9 25 when it is introduced into the top of the tube. The suction produced by the weight 9 as it descends in the tube is sufficient to hold the door 21 in its closed position, but if a more positive action is desired the door 30 21 may be provided with a suitable latch for holding it closed.

When the device is to be used the operator deposits the weight 9 in the top of the vertical passage. The weight is immediately and quietly deposited on the floor again, and the operation is repeated as often as desired.

The balls 9 may be made in various weights. For example, the ball, if made of 40 solid iron, may weigh about 10 pounds and may be made lighter by hollowing out the interior of the ball, as shown at 9^b Fig. 3, without changing the outside dimensions. Likewise, the ball may be made heavier by 45 hollowing it out and filling the internal cavity with lead or some substance that is considerably heavier than iron.

The operation of this device is practically noiseless and free from vibration. A 50 15-pound weight can be made to drop through the machine without the noise being noticed outside the room in which the machine is being operated.

As stated above, the operator can readily 55 calculate what amount of work he has done by counting the number of times he passes the weight through the machine. For instance, if a 10 pound ball is passed ten times, the operator has lifted 100 pounds 60 from the floor to the top of the tube, and if a 10 pound ball is lifted 100 times, the operator will have lifted a half ton to the top of the tube.

It will be understood that various changes 65 in the construction and arrangement of

parts may be made without departing from my invention as set forth in the appended claims.

I claim as my invention:

1. An exercising device comprising a member defining a vertical passage, a weight suitable for producing bodily exercise by repeated lifting, said weight being adapted to fall thru said passage, and pneumatic means made effective by the downward movement of said weight thru said passage for cushioning the fall of the said weight. 75

2. An exercising device comprising a member defining a vertical passage, a weight suitable for producing bodily exercise by repeated lifting, said weight being adapted to fit slidingly within said passage, and being adapted to cause, by its movement thru said passage, abnormal pressure which is effective to check the fall of said weight, 80 and a door for closing one end of said passage. 85

3. An exercising device comprising a member defining a vertical passage, a weight suitable for producing bodily exercise by repeated lifting, said weight being adapted to fit slidingly within said passage and being adapted to cause, by its movement thru said passage, abnormal pressure which is effective to check the fall of said weight, a door for closing one end of said passage, and means 90 at the bottom of said passage for absorbing the shock of the descending weight. 95

4. An exercising device comprising a hollow base, a cushioning pad within said base and having a concave upper surface, an outlet opening in said base, a vertical tube carried by said base, and a weight suitable for producing bodily exercise by repeated lifting, said weight fitting slidingly within said tube and being adapted, by its movement thru said tube, to produce abnormal pressure which is effective to check the fall of the said weight. 100 105

5. An exercising device comprising a hollow base, a cushioning pad within said base and having an inclined concave upper surface, an outlet opening in said base, a vertical tube carried by said base, a weight fitting slidingly within said tube, said weight being suitable for producing bodily exercise by repeated lifting, and being adapted by its movement thru said tube to produce abnormal pressure which is effective to check the fall of said weight, and a door for closing the opening in said base. 110 115

6. An exercising device comprising a member defining a vertical passage, a weight fitting slidingly within said passage, said weight having a covering of soft material 125 adapted to frictionally engage the walls of said passage and being adapted to produce, by its movement thru said passage, abnormal pressure which is effective to check the fall of said weight. 130 135

7. An exercising device comprising a hollow base having a lateral opening, a cushioning pad disposed in said base, a swinging door for closing said opening, a vertical tube carried by said base, a second tube in adjustable telescoping relation to said first-named tube, and a weight fitting slidably within said vertical tube, said weight being suitable for producing bodily exercise by repeated lifting, and being adapted, during its descent into said tube, to produce abnormal pressure which is effective to check the fall of the said weight.

In testimony whereof I, the said GEORGE E. SMITH, have hereunto set my hand.

GEORGE E. SMITH.
